FIG. 2.

FIG. 1.

INVENTOR.
Carl W. Newton
BY *W. G. Doolittle*
ATTORNEY

UNITED STATES PATENT OFFICE

96,623

DESIGN FOR A PITCHER OR SIMILAR ARTICLE

Earl W. Newton, Evanston, Ill., assignor to Imperial Glass Corporation, Bellaire, Ohio, a corporation of Ohio

Application July 11, 1935, Serial No. 57,593

Term of patent 7 years

To all whom it may concern:

Be it known that I, Earl W. Newton, a citizen of the United States, residing at Evanston, in the county of Cook and State of Illinois, have invented a new, original, and ornamental Design for a Pitcher or Similar Article, of which the following is a specification, reference being had to the accompanying drawing, forming part thereof.

In the drawing:

Fig. 1 is an elevational view of a pitcher or similar article, showing my design; and

Fig. 2, a top plan view.

I claim:

The ornamental design for a pitcher or similar article, as shown.

EARL W. NEWTON.
